(57) **CLAIM**

The ornamental design for a slicer, as shown and described.

DESCRIPTION

FIG. 1 is a top front right side perspective view of a slicer showing my new design, the handle portion which is not claimed being represented by dot-dash lines;

FIG. 2 is a bottom rear left-side perspective view thereof;

FIG. 3 is a front view thereof;

FIG. 4 is a left-side elevational view thereof, the right-side being mirror symmetrical thereto; and,

FIG. 5 is a top view thereof.
